PAPER BOX MACHINE

Edwin G. Staude, Minneapolis, Minn., assignor
to E. G. Staude Manufacturing Company, St.
Paul, Minn., a corporation of Minnesota

Application May 19, 1941, Serial No. 394,087

6 Claims. (Cl. 93—50)

This invention relates to new and useful improvements in machines for making paper boxes and particularly paper boxes which are first made into long flat tubes and which tubes are then slitted transversely to provide a plurality of relatively shorter box tubes.

I am aware that machines have been previously built for this purpose, but to the best of my knowledge, in all such machines the transverse slitting is done immediately after the tube blank has been glued, and before the glue has had sufficient time to set. This frequency results in a slight disarrangement of the overlapping glued edge portions of the blank from which the tube is constructed, causing the glued seams of the short tubes subsequently to be formed, to be inaccurate, and in some instances, the seams of the short tube sections may not be glued at all.

Another disadvantage in cross slitting the relatively long flat tubes before the glue has set, or at least partially set, is that the wet glue has a tendency to accumulate on the slitting rolls and may eventually affect the operation thereof.

To overcome the difficulties above enumerated, I propose to feed the glued flat tubes through a pressure unit comprising co-acting conveyer belts between which the flat tubes are fed in overlapping relation and whereby a uniform pressure is applied to a plurality of tubes as they are fed between said belts, the length of said pressure unit being such that when the flat tubes are discharged therefrom, the glue has set sufficiently to prevent the glued seams from opening or becoming disarranged when the tubes are substantially fed through the slitting unit.

In the formation of the flat tubes, as herein disclosed, the blanks from which the box is made may be fed through a folding and gluing machine similar to the one shown in my Patent No. 1,104,013 or my Patent No. 2,008,049, wherein the flat, elongated blanks are folded along longitudinally disposed score lines to provide flat tubes, glue being applied between the overlapping edges of the blanks to provide a glued seam. After the blanks have passed through the folding and gluing machine, and have been folded into long flat collapsed tubes, the glued tubes are immediately fed through a pressure unit in overlapping relation, while the glue is still wet, which pressure unit may be of the type disclosed in my Patent No. 2,133,727. This unit exerts uniform pressure on the blanks to insure firm adhesive sealing of the glue and prevent opening of the blanks while under such pressure. The pressure unit is of

such length that when the elongated, flat tubes are discharged therefrom, the glue has set sufficiently to prevent opening of the glue seam.

An object of the present invention, therefore, is to provide an improved apparatus for folding flat blanks into tubes and uniting the opposed longitudinal edges of the blanks by a suitable adhesive, and then delivering the glued flat tubes to a pressure unit which acts to hold the glued seams of the blanks in proper position until the glue has set sufficiently to permit the blanks to be fed from the pressure unit to a slitting mechanism, wherein each tube is slitted transversely into a plurality of relatively shorter box tubes, and whereby the seams of the relatively shorter box tubes cannot "pop" open, or become unglued, as frequently occurs when the tubes are cross-slitted before the glue has set.

In the accompanying drawings, I have shown a plurality of mechanisms which have been combined to form a machine capable of performing the various steps of the invention in a highly efficient and practical manner and whereby the operation of making shorter box tubes may be greatly expedited.

Other objects of the invention will appear from the following description and accompanying drawings and will be pointed out in the annexed claims.

In the accompanying drawings there has been disclosed a structure designed to carry out the various objects of the invention, but it is to be understood that the invention is not confined to the exact features shown as various changes may be made within the scope of the claims which follow.

In the drawings:
Figure 1 is a plan view of a tube slitting unit shown positioned to receive glued flat tubes from a pressure unit;

Figure 2 is a cross-sectional view on the line 2—2 of Figure 1, showing the means for transferring the relatively shorter box tubes from the slitting unit to a suitable receiving conveyer;

Figure 3 is a longitudinal sectional view on the line 3—3 of Figure 1, showing the means for feeding the flat tubes from the pressure unit, one at a time, onto a transverse conveyer which delivers the tubes to the slitting unit;

Figure 4 is a cross-sectional view on the line 4—4 of Figure 3, with some of the parts omitted;

Figure 5 is a longitudinal sectional view of the pressure unit, with some of the parts omitted;

Figure 6 is an enlarged detail sectional view showing the feed wheel at the discharge end of

the pressure unit and the means for accurately positioning the long, flat tubes on the transverse conveyer;

Figure 7 is an enlarged detail sectional view showing a mechanism for transferring the shorter box tubes from the slitting unit onto a slow moving receiving belt or conveyer, in overlapping relation;

Figure 8 is an enlarged detail view, partially in section, showing a plurality of pairs of cooperating slitting rolls;

Figure 9 is a view showing one end of a creased blank from which a tube of considerable length is formed;

Figure 10 is a view showing a creased blank folded longitudinally and its overlapped edges glued together to form a tube;

Figure 11 is a view showing a tube transversely slitted to provide a plurality of relatively shorter box tubes;

Figure 12 is a perspective view showing one of the shorter box tubes extended to form a small rectangular box with open ends; and

Figure 13 is a perspective view showing an elongated tube collapsed, as when fed through the pressure unit.

The present invention, as hereinbefore stated, is directed primarily to the manufacture of collapsible box tubes adapted for use in packaging various articles. To expedite the manufacture of such tubes, a plurality of short tubes 2, as shown in Figure 12, are cut from a relatively longer tube 3, shown in Figures 10 and 11, by transversely slitting the longer tube, as indicated at 4 in Figure 11. The longer tubes 3 are made from preformed elongated blanks, which are longitudinally scored, as indicated at 5, 6, 7, and 8, in Figure 9, after which one or more of the marginal side edge portions of the blank may have a suitable glue applied thereto, as indicated at 9 in Figure 10. The blank is then longitudinally folded along the score lines 5, 6, 7, and 8, and the glued marginal edges thereof overlapped to provide a seam 10, shown in Figures 10, 11, and 12. Each elongated tube 3 thus formed, is open at both ends, whereby it may readily be collapsed so that its walls are disposed in flatwise relation, as clearly illustrated in Figure 13. To complete the formation of the finished box tubes 2, each relatively longer tube 3 is transversely slitted or severed, as shown in Figure 11, whereby a plurality of relatively shorter box tubes 2 are formed from each elongated tube 3, as will subsequently be described.

The formation of the tube 3, as above described, may be accomplished in box making and gluing machines of the general type disclosed in my above mentioned Patent No. 1,104,013 or No. 2,008,049, and therefore the mechanisms for forming the relatively longer tubes 3 need not be described in detail in the present application.

In machines now commonly used for transversely slitting long tubes into a plurality of relatively shorter box tubes, the slitting of the long tubes is usually performed before the glue seam has had an opportunity to dry sufficiently to prevent displacement of the marginal edges of the blank which constitute the glued seam. As a result, the finished box tubes are not always uniform, because the glue coated marginal edges of the blank frequently become displaced while the long box tubes are being transferred from the gluing and folding machine 11, to the slitting mechanism, or the seam may become displaced during the slitting operation.

An important feature of the invention resides in the manner of conveying or transferring the freshly glued tubes 3 from the folding and gluing mechanisms, partially shown at 11 in Figure 5, to the slitting mechanism, subsequently to be described.

In the present invention, the above mentioned difficulty has been completely eliminated by the provision of means for temporarily holding the freshly glued elongated tubes under pressure, during a portion of the time they are traveling from the gluing and folding mechanism 11 to the slitting mechanism, whereby when the flat tubes subsequently reach the slitting mechanism, the glued edge portions of the tube cannot become displaced.

A means for thus applying pressure to the freshly glued elongated tubes is shown in Figure 5, and consists of a pressure unit, generally designated by the numeral 12. This unit may be similar to the apparatus shown and described in my Patent No. 2,133,727, and therefore need not be shown and described in detail herein.

As best shown in Figure 5, the pressure unit 12 is arranged to receive the elongated box tubes from the folding and gluing machine 11, and comprises an endless belt 13 trained about a series of idler rollers or pulleys 14, 15, 16, 17, 18, a drive pulley or drum 19, idler roller 20, and a belt tightener roller 21, all mounted in a suitable supporting frame 22 which may be carried by suitable cross frame members or standards 23 and 24. The drive pulley or drum 19 is shown driven by a worm gear drive 23' from one end of a suitable drive shaft 24' disposed lengthwise of the machine, and mounted in suitable bearings, not shown. The opposite end 25 of the shaft 24' is operatively connected to the driving mechanism of the blank gluing and folding machine by suitable means, not shown. The belt 13 travels at a relatively slower speed than the conveyer belts 26 and 27 of the folding and gluing machine, and has an inclined portion 28 positioned to be engaged by the leading ends of the tubes 3, as they are fed from the gluing and folding machine. The upper portion 29 of the conveyer belt 13 of the pressure unit is preferably disposed at an elevation above the path of travel of the tubes in the folding and gluing machine.

By thus arranging the upper run 29 of the belt 13, the leading end of each tube will impinge against the inclined belt portion 28, as the tubes are successively fed from the gluing and folding machine by the conveyer belts 26 and 27 thereof. Because of the pressure unit belt 13 operating at a relatively slower speed than the belts 26 and 27, the tubes are caused to overlap on the belt 13, in a lengthwise direction, into a continuously moving stack of tubes, as clearly illustrated in Figure 5.

The pressure unit 12 has a complementary endless belt 31 disposed directly over the path of travel of the stack of tubes on the belt 13. The belt 31 is supported on a drive pulley 32 and an idler pulley 33. A belt tightener pulley 34 is shown provided for tensioning the belt. The lower run of the belt 31 is arranged to engage the upper surfaces of the tubes on the belt 13, and is held firmly thereagainst by weighted rollers 35 supported between suitable links 36, as will readily be understood by reference to Figure 5. Additional weighted rollers 37 engage the top of the stack of tubes at the tail end of the pressure belt 31.

The belt 31 is driven from the shaft 24 through

a worm gear drive, indicated at 38 in Figure 5, and a chain 39 which operatively connects the worm gear drive 38 to a gear drive 41 which, in turn, drives the shaft 40 of the pulley 32. The pulley 32 is mounted for vertical adjustment by a suitable device, indicated at 42 in Figure 5. The pressure belt 31 and its supporting rollers 32, 33, and 34 are mounted in a suitable frame 38, pivotally supported at one end on the shaft 40, and whereby the lower run of the pressure belt 31 rides freely on the top of the stack of tubes, as will be readily understood by reference to Figure 5.

By reference to Figure 5, it will be noted that a portion of the upper run of the conveyer belt 13 is supported on suitable supporting plates 43 and 44, and spaced side plates 45 are provided at the receiving end of the pressure unit 12 for guiding the tubes between the belts 13 and 31. Similar guides or side walls 46 are provided at the discharge end of the pressure unit 12, as shown in Figures 5 and 6.

A feed wheel 47 is provided at the discharge end of the pressure unit 12 and is secured to a suitable shaft 48 mounted in bearings 49 provided in the side portions of an upright frame member 48', shown secured to the cross member of the pressure unit frame by suitable spacing brackets 49', as shown in Figure 3. The feed wheel has a gripping surface 51 adapted to coact with the periphery of a relatively smaller feed wheel 52 to grip the leading end of each tube and feed it from the pressure unit, as will readily be understood by reference to Figure 6. The smaller feed wheel 52 is secured to a shaft 53 mounted in suitable bearings provided in the side frame members, as shown in Figure 4.

A suitable friction element or block 54 is provided immediately in front of the feed wheels 47 and 52, and is secured to a hinged member 55 interposed between the feed wheels and a bottom guide plate 59'. The friction element 54 operates to retard the next following tube and allows but one tube to be fed from the pressure unit at a time. The friction element 54 is provided with an adjusting device, generally designated by the numeral 55, whereby said element may be accurately adjusted with respect to the periphery of the feed wheel 47, to positively limit the feeding of the tubes from the pressure unit to the transfer unit, one at a time.

The shaft 53 of the lower feed wheel 52 is driven from a cross shaft 57 by a pair of gears 58 and 59, the cross shaft 57 having a driving connection with a power shaft 56 by a bevel gear drive 61, as indicated in dotted lines in Figure 3 and full lines in Figure 4. The power shaft extends lengthwise of the pressure unit 12 and is operatively connected to the driving mechanism of the gluing and folding machine 11 by suitable means, not shown. The shaft 48 of the upper feed wheel 47 is driven by a pair of gears 62 and 63, the pitch diameters of which are such that their point of contact is located substantially in the path of travel of the blanks, where the blanks enter between the feed wheels 47 and 52. To prevent accumulation of foreign matter on the periphery of the feed wheel 47, a suitable brush 64 is shown mounted on a cross shaft 65, directly above the feed wheel 47, and is adapted to engage the periphery of the feed wheel, as shown in Figure 3. The brush may be driven by a belt drive 66 from the shaft 48 of the feed wheel 47, as shown in Figure 4.

The right angle transfer unit and slitting

mechanism, generally designated by the numerals 67 and 68, respectively, are shown comprising a single supporting frame whereby the mechanism may be assembled as a unitary structure, independently of the pressure unit and gluing and folding machine.

As best shown in Figures 2, 3, and 4, the supporting frame of the right angle transfer unit and slitting mechanism comprises the frame member 48' and a frame member 71 secured to the member 48' by suitable tie members 72, cooperating therewith to provide a rigid frame which, as shown in Figure 3, is attached to the end frame member 23 of the pressure unit 12 by the spacing brackets 49'. The power shaft 56, as hereinbefore stated, is carried by the frame of the pressure unit 12, and the cross shaft 57 by the upright frame member 48' of the right angle transfer unit. The cross shaft 57, however, is so arranged with respect to the power shaft 56 that when the frame member 48' is coupled to the end frame member 23 of the pressure unit by the brackets 49', the shafts 56 and 57 will be operatively connected together by the bevel gear drive 61.

The transfer unit 67 is shown comprising a relatively wide belt 73 substantially aligned with the belt 13 of the pressure unit 12. The upper run 74 of the belt 73 is horizontally supported on idler rollers 75 and 76, in position to receive the elongated tubes from the feed wheels 47 and 52. The belt 73 has running connections with idler rollers 77 and 78, and a belt tightening roller or pulley 79, mounted on an adjustable bracket 81. The belt also has a running connection with a drive pulley or drum 82 secured to a cross shaft 83 driven by a chain drive 84 from the shaft 53, as indicated in Figures 3 and 6.

The idler roller 75 is rotatably mounted in suitable bearings provided in complementary brackets 80 and 80' and the roller 76 is shown journaled in brackets 85 and 85'. The brackets 80 and 80' are secured together in spaced relation by a cross rod 86, and the brackets 85 and 85' are similarly secured together by a rod 86. The brackets 80 and 80' are adjustable lengthwise of the belt by threaded shafts 87, each having one end rotatably supported in the frame member 48', as indicated at 88 in Figure 3. The opposite ends of said shafts are rotatably supported in the end frame member 71. The shafts 87 are operatively connected together for simultaneous rotation by a chain drive 89, best shown in Figure 1. One of the shafts 87 is shown having a squared end portion 91, whereby a suitable crank or other operating member may be connected thereto for rotating the shafts. Rotation of the shafts 87 will longitudinally adjust the brackets 85 and 85' thereon.

The brackets 85 and 85' which support the idler roller 76, are adjustable towards and away from the brackets 80 and 80', by threaded shafts 94, each having one end rotatably supported in the frame member 48', as shown at 95 in Figure 1. The opposite ends of said threaded shafts are rotatably supported in the frame member 71. A chain drive 96 connects together the shafts 94 for simultaneous rotation. One of the shafts 94 is provided with a squared terminal 97, whereby the shafts 94 may be relatively rotated in a manner similar to the shafts 87, thereby to adjust the positions of the brackets 85 and 85' with respect to the brackets 80 and 80'.

To properly position the flat tubes on the belt run 74, a cam element 98 is mounted on a shaft

99 directly over the tubes, adjacent to the feed wheels 47 and 52. A rotary brush 101 is also mounted over the belt run 74 and is adapted to engage each blank and feed it forwardly against a suitable stop bar 102, shown provided with a horizontally disposed guide plate 103 adapted to guide the forward end of the tube into engagement with the stop bar 102, as clearly illustrated in Figure 3. The brush 101 is vertically adjustable by a suitable adjusting device 104, and is driven by a chain drive 105 from the cross shaft 99 supporting the cam element 98. The cross shaft 99, in turn, is driven from the shaft 48 of the feed wheel 47 by a suitable chain drive 106.

The conveyer belt 73 operates at a speed substantially equal to the speed of travel of the tubes delivered thereto by the feed wheels 47 and 52, and the function of the cam element 98 is to deflect the trailing end of each tube downwardly into the path of the next following tube and onto the belt run 74, into position to be engaged by the means for laterally feeding the blanks from their normal path of travel into the slitting mechanism 68.

The means provided for laterally feeding the blanks from the upper run 74 into the slitting mechanism 68, is shown comprising a pair of spaced parallel endless chains 107 and 108 disposed at right angles to the belt 73. The upper run of the chain 108 is located in close proximity to the roller 75 and travels in a suitable channel or guide 109 provided in the brackets 80 and 80'. The chain 107 travels in a similar guide 109 provided in the brackets 85 and 85', as shown in Figures 3 and 6. From the foregoing, it will thus be noted that the effective length of the belt run 74 may be varied to suit box tubes of different lengths by the simple manipulation of the adjusting shafts 87 and 94. Each chain 107 or 108 is mounted on idler sprockets 112, 113, and 114, and a drive sprocket 115. The drive sprockets 115 are splined to a shaft 116, whereby they are adapted for free sliding movement thereon. The shaft 116 is supported in suitable bearings in the frame members 48' and 71. The chains 107 and 108 have spaced lugs 117 thereon which extend upwardly above the surface of the belt run 74, whereby said lugs may engage one edge of each tube supported on the belt run 74 and thereby laterally feed the tubes from beneath the rotating brush 101 into the slitting mechanism 68. The tubes are held in position on the belt run 74 and chains 107 and 108 by the guide or shield 103 and a pair of suitable hold down bars 118, shown in Figure 1.

The idler sprockets 112 of the chains 107 and 108 are mounted on studs secured to one end of arcuately formed arms 119, pivoted at 121 to the brackets 80' and 85'. The arms 119 are adjustably secured to their respective brackets by adjusting screws 122 received in slots 123 provided in the brackets 80' and 85', as best shown in Figure 2. By relatively adjusting the arms 119 upon their respective brackets, the sprockets 112 may be adjusted to properly position the upper runs of the chains 107 and 108 with respect to the slitting mechanism.

The idler sprockets 113 at the opposite ends of the upper runs of the chains 107 and 108 are mounted on studs adjustably secured to horizontally disposed slotted arms 123 secured to the brackets 80 and 85, whereby the sprockets 113 may be adjusted to properly tension the belts 107 and 108.

The lower idler sprockets 114 are mounted on studs secured to depending arms 124 of the brackets 80 and 85. To axially move the drive sprockets 115 on the shaft 116, when the chains are laterally adjusted by manipulation of the shafts 87 and 94, the brackets 80' and 85' are provided with arms 125 having their lower terminals engaging annular grooves in the sprockets 115, whereby lateral adjustment of the brackets 80' and 85' will similarly adjust the drive sprockets 115 upon the shafts 116, as will readily be understood by reference to Figure 2.

The slitting mechanism 68, next to be described, is shown comprising a plurality of upper and lower complementary wheels 126 and 127 mounted on shafts 128 and 129, respectively, journaled in suitable bearings provided in the side frame members 48' and 71. Cutting disks 131 are detachably secured to the upper wheels 126 and cooperate with complementary disks 132 secured to the lower wheels 127 to transversely sever the long box tubes fed to the wheels 126 and 127. The wheels 126 and 127 are adjustable longitudinally on the shafts 128 and 129 to vary the length of the relatively short box tubes cut from the long tubes.

The upper shaft 128 is vertically adjustable with respect to the lower shaft 129 by suitable means, not shown, to vary the gap or space between the peripheries of the wheels 126 and 127 in accordance with the thickness of the tube blanks being fed therebetween, as will be understood by reference to Figure 7. The shafts 128 and 129 are geared together for simultaneous operation by suitable gears 133 and 134, as shown in Figure 4. The wheels 126 and 127 are driven from the cross shaft 57 through a pair of bevel gears 135 and 136, the pinion 135 being secured to the shaft 57 adjacent to a bearing bracket 137 which supports one end of the shaft 57. The bevel gear 136 is mounted on a stub shaft 138 rotatably mounted in a bracket 139 secured to the frame member 48', as clearly illustrated in Figure 4.

A pinion 141 is secured to the inner end of the stub shaft 138 and meshes with the lower spur gear 134, whereby when the shaft 57 is rotated, the gears 133 and 134 will be rotated in opposite directions to drive the shafts 128 and 129.

The severed box tubes are fed from the slitting rolls 126 and 127 between the adjacent runs 142 and 143 of a plurality of spaced endless belts 144 and 145, which belts operate to feed the severed box tubes onto a slow moving delivery belt 146, mounted on rollers 147 and 148, secured to shafts 147' and 148', respectively, journaled in brackets 150, secured to the frame members 48' and 71, as best shown in Figure 2. The belts 144 and 145 of each pair of such belts are preferably disposed in a common vertical plane, and the belts 144 are alternately arranged with the upper cutting wheels 126, and the belts 145 are similarly arranged with the lower cutter-supporting wheels 127, as will be clearly understood by reference to Figure 1. In other words, one pair of belts 144 and 145 is preferably provided for each short box tube severed from the long tubes delivered to the slitting wheels 126 and 127.

Each belt 144 is mounted on a drive pulley 148, and anti-friction pulleys 149, 151, and 152, the latter being adjustably supported in a slot 153 provided in a carrier 154, adjustably secured to a cross member 155 by bolts 153'. The cross member 155 is suitably secured to the side frame members 48' and 71, as will be understood by reference to Figure 1. The idler pulleys 149 and 151 are supported on adjustable arms 156 and

157, respectively, mounted for pivotal adjustment on the carrier 154, as clearly illustrated in Figure 7. Adjustment of the arms 156 and 157 will vary the gap between the belt runs 142 and 143 of each pair of belts 144 and 145. Each lower belt 145 is supported in a similar manner on a drive sheave or pulley 158 and anti-friction idler pulleys 159, 161, and a belt tightener pulley 162 adjustably mounted in a slot 163 provided in a lower carrier 164. Pulleys 165 are provided on each lower carrier 164 for supporting the intermediate portions of the belt runs 143 of the belts 145. The small diameter of the anti-friction pulleys 149 and 159 allows the belts 144 and 145 to extend into the spaces between the cutting wheels 126 and 127 mounted on the shafts 128 and 129, respectively, as clearly illustrated in Figure 7. The belt runs 142 and 143 cooperate to firmly grip the severed box tubes and convey them to the delivery conveyer 146.

The lower carriers 164 are adjustably mounted on spaced parallel cross bars 166 secured to the machine frame, as will be clearly understood. The drive pulleys 148 and 158 are mounted on upper and lower shafts 167 and 168, journaled in bearings in the side frame members 48' and 71. The upper shaft 167 is driven from the gear 133 secured to the cutter shaft 128, through an intermediate gear 169, and the lower shaft 168 is driven from the gear 134 of the shaft 129 through a similar intermediate gear 171. The pulleys 148 and 158 are splined to their respective shafts 167 and 168, whereby they may be axially adjusted on said shafts in accordance with the length of the relatively shorter box tubes to be cut from the long tubes being delivered to the cutting wheels 126 and 127 from the transfer unit 68. The severed box tubes 2 are delivered to the delivery conveyer 146 from the belts 142 and 143 and are directed downwardly into closely packed overlapped relation thereon by a small roller 174. A triangularly shaped cross bar 175, arranged below the roller 174, cooperates with the roller 174 to properly position the short box tubes on the conveyer belt 146, as shown in Figure 7. The roller 174 is supported by suitable arms 176 which may be adjustably secured to the cross bar 155, as shown in Figure 2. A relatively larger roller 177 is mounted adjacent to the roller 174 and cooperates therewith to guide or feed the short tubes 2 into uniform overlapping relation on the delivery belt 146.

The roller 177 is adjustably supported by a pair of arms 178 pivotally mounted on brackets 179 which, in turn, are mounted in threaded engagement with a pair of threaded rods or shafts 181 mounted for rotation in suitable bearings provided in the brackets 150, as will be understood by reference to Figures 2 and 4. The outer ends of the threaded shafts 181 are operatively connected together by a chain drive 182, whereby said shafts are adapted for simultaneous rotation, thereby to effect longitudinal adjustment of the upright brackets 179 thereon, and whereby the location of the roller 177 with respect to the roller 174 may be varied. The roller 177 is also vertically adjustable by means of adjusting screws 183, one such screw being received in threaded engagement with each arm 178 and having their lower ends engaging fixed portions of the brackets 150. The arms 178 are shown connected together by a suitable tie rod 184 and a similar tie rod 185 connects together the upright brackets 179, as shown in Figure 2.

Means is provided for driving the roller 177 and

is shown comprising a chain 186 having a running connection with a sprocket 187 suitably fixed to one end of the roller 177 and having a driving connection with a sprocket 188 secured to the shaft 147' of the roller 177. An idler sprocket 189 is mounted on one of the brackets 150 adjacent to the sprocket 188 and operates to hold the chain in driving engagement with the sprocket 188. A belt tightener sprocket 191 is mounted in an arm 192 pivoted at 193 to one of the brackets 150. The arm 192 has a relatively shorter arm 194 disposed at substantially right angles thereto, and a spring 195 is connected to one end of the arm 194 and to a cross member or bar 196 provided at the outer ends of the brackets 150. The spring 195 constantly urges the arm 192 in a direction to maintain the chain 196 taut, regardless of the position of the roller 177 with respect to the relatively smaller roller 174.

20 A suitable supporting plate 197 is provided beneath the upper run of the delivery belt 146 to provide a support therefor. From the delivery conveyer 146, the completed box tubes are delivered onto a suitable receiving table 198 in rows of overlapping tubes from which table the completed tubes may be removed by an attendant.

25 The delivery conveyer 146 is driven from the shaft 168 by means of a suitable speed reducer, generally designated by the numeral 199, mounted on the shaft 147' and having a ring gear 201 meshing with a pinion 202 secured to the shaft 168, as will be understood by reference to Figures 1 and 2.

30 As the combined gluing and folding machine 35 and the pressure unit 12 may sometimes be used without the slitting unit 68, the combined transfer and slitting units are supported on a single supporting frame, hereinbefore described, which is detachably connected to the end frame member 23 of the pressure unit by the brackets 49', shown in Figure 3. To facilitate moving the combined transfer and slitting unit about, when detached from the pressure unit, the frame of the slitting unit is shown provided with suitable 40 caster wheels 203, swiveled to the lower horizontal portions of suitable angle plates or brackets 204, vertically slidable on the frame members 72 of the slitting unit, as indicated at 205 in Figure 3. Shouldered shafts 206 are rotatably mounted 45 in bearings provided in the frame members 72, and have lower threaded end portions 207 received in threaded hubs 208 provided in the horizontal portions of the brackets 204. Each shaft 206 is shown having an annular collar or shoulder 209 adapted to take the upward thrusts of the shafts 206, when the slitting unit is carried on the caster wheels 203. Bevel pinions 210 are secured to the upper ends of the shafts 206 and mesh with pinions 211 secured to shafts 212 mounted in bearings provided in the end brackets 48' and 71. One end of each shaft 212 projects beyond the frame member 71, as shown at 213 in Figure 3, whereby a suitable operating crank 50 may be applied thereto for rotating the shafts 212 to vertically adjust the caster wheels 203 with respect to the machine frame and thereby transfer the load from the feed 214 of the machine frame onto the caster wheels 203, or vice versa, as will readily be understood by reference to Figure 3. If desired, a separate shaft 212 may be provided for each pair of caster wheels 203 provided at each side of the machine, or, if desired, said shafts may be connected together by 55 a suitable chain, not shown, for simultaneous

operation, in a manner similar to the adjusting shafts 84.

From the foregoing, it will be noted that by the unique arrangement of the various mechanisms herein disclosed, such as the gluing and folding machine, pressure unit, transfer unit, slitting unit, and delivery belt, the operation of manufacturing relatively short box tubes may be greatly expedited. This results because the material from which the completed short tubes are made travels substantially without interruption through the machine, except for the slight intermittent interruption at the transfer unit where the chains 107 and 108 laterally feed the long tubes from their normal path of travel to the slitting mechanism.

An important feature of the invention, as hereinbefore stated, resides in the provision of the pressure unit 12 between the gluing and folding machine and the slitting unit, which receives the freshly glued elongated tubes from the blank folding and gluing machine and conveys them under pressure to the transfer unit, whereby freshly glued overlapping edge portions of said blanks are held in adhesive relation sufficiently long to permit the glue to set or dry to the extent that the glued seams of the box tubes cannot become disarranged or open up, when the blanks are fed from their normal path of travel by the transfer unit into the slitting mechanism. In other words, the travel of the freshly glued tubes from the gluing and folding machine to the cutting mechanism is so timed that when the tubes reach the cutting or slitting mechanism 68, the glue is sufficiently dry to permit the elongated tubes to be transversely cut into a plurality of relatively shorter box tubes, without danger of distorting the glued seams of said tubes. It will also be noted by reference to Figures 1, 2, and 7, that the relatively shorter box tubes 2 are delivered onto the delivery conveyor or belt 146 in stacked relation, and in closely arranged parallel rows of stacks, as partially shown in Figure 1, whereby the finished box tubes may readily be removed from the receiving table 198 by an attendant and bound into bundles or otherwise disposed of.

It will be apparent to those skilled in the art that I have accomplished at least the principal objects of my invention, and it will also be apparent to those skilled in the art that the embodiments herein described may be variously changed and modified, without departing from the spirit of the invention, and that the invention is capable of uses and has advantages not herein specifically described; hence, it will be appreciated that the herein disclosed embodiments are illustrative only, and that my invention is not limited thereto.

I claim as my invention:

1. In a paper box machine adapted to automatically feed in timed relation, a series of blanks to be glued and folded into tubes, including suitable glue applying mechanism, folding mechanism, and means for delivering the glued and folded tubes onto a slow moving pressure conveyor in lapped relation, means for feeding the foremost tubes, one at a time, from the pressure conveyor, as the tubes successively emerge therefrom, a right angle transfer section adapted to receive said tubes from the pressure conveyor and advance them at right angles to the direction of initial travel of the tubes, means for positioning the tubes on the transfer section, slitting means positioned to receive said tubes from the transfer

section and transversely sever each tube into a plurality of relatively shorter box tubes, and means for delivering the shorter box tubes onto a slow moving conveyor in overlapped relation.

5. In a paper box machine adapted to automatically feed in timed relation, a series of blanks to be glued and folded into tubes, including suitable glue applying mechanism, folding mechanism, and means for delivering the glued and folded tubes onto a slow moving pressure conveyor in lapped relation, means for feeding the topmost tubes, one at a time, from the pressure conveyor, as the tubes successively emerge therefrom, a right angle transfer section adapted to receive said tubes from the pressure conveyor and advance them at right angles to the direction of initial travel of the tubes, means for positioning the tubes on the transfer section, slitting means positioned to receive said tubes from the transfer section and transversely sever each tube into a plurality of relatively shorter box tubes, and means for delivering the shorter box tubes onto a slow moving conveyor in overlapped relation.
10. In a paper box machine adapted to automatically feed in timed relation, a series of blanks to be glued and folded into tubes, including suitable glue applying mechanism, folding mechanism, and means for delivering the glued and folded tubes onto a slow moving pressure conveyor in lapped relation, means for feeding the topmost tubes, one at a time, from the pressure conveyor, as the tubes successively emerge therefrom, a right angle transfer section adapted to receive said tubes from the pressure conveyor and advance them at right angles to the direction of initial travel of the tubes, means for positioning the tubes on the transfer section, slitting means positioned to receive said tubes from the transfer section and transversely sever each tube into a plurality of relatively shorter box tubes, and means for delivering the shorter box tubes onto a slow moving conveyor in overlapped relation.
15. In a paper box making machine, means for advancing preformed blanks along a predetermined path in timed relation, glue applying mechanism, means for folding each blank into an elongated flat tube, a pressure conveyor into which the flat tubes are delivered in endwise direction from said advancing means, said pressure conveyor holding the glued wall portions of the tube in bonding engagement until the glue has set, means for feeding the foremost tubes, one at a time, from the pressure conveyor, as the tubes successively emerge therefrom, a right angle transfer section adapted to receive said elongated tubes from the pressure conveyor and laterally move them out of the initial path of travel of the tubes, means for accurately positioning the elongated tubes on the transfer section, a slitting mechanism positioned to receive said tubes from the transfer section and transversely sever each tube into a plurality of relatively shorter box tubes, and means for delivering the shorter box tubes onto a suitable receiving means.

20. In a paper box making machine, means for advancing preformed blanks along a predetermined path in timed relation, glue applying mechanism, means for folding each blank into an elongated flat tube, a pressure conveyor into which the flat tubes are delivered in endwise direction, to a pressure conveyor, said pressure conveyor operating at a relatively slower speed than the tubes are fed thereto, whereby the flat tubes are delivered thereto, in lapped relation, means for feeding the tubes, one at a time, from the pressure conveyor, a right angle transfer section adapted to receive said tubes from the pressure conveyor and laterally move them out of the initial path of travel of the tubes, means for accurately positioning the elongated flat tubes on the transfer section, a slitting mechanism positioned to receive said tubes from the transfer section and transversely sever each tube into a plurality of relatively shorter box tubes, and means for delivering the shorter box tubes onto a slow moving conveyor in overlapped relation.
25. In a paper box making machine, means for advancing preformed blanks along a predetermined path in timed relation, glue applying mechanism, means for folding each blank into an elongated flat tube, means for delivering the flat tubes in endwise direction, to a pressure conveyor, said pressure conveyor operating at a relatively slower speed than the tubes are fed thereto, whereby the flat tubes are delivered thereto, in lapped relation, means for feeding the tubes, one at a time, from the pressure conveyor, a right angle transfer section adapted to receive said tubes from the pressure conveyor and laterally move them out of the initial path of travel of the tubes, means for accurately positioning the elongated flat tubes on the transfer section, a slitting mechanism positioned to receive said tubes from the transfer section and transversely sever each tube into a plurality of relatively shorter box tubes, and means for delivering the shorter box tubes onto a slow moving conveyor in overlapped relation.
30. In a paper box making machine, means for advancing preformed blanks along a predetermined path in timed relation, glue applying mechanism, means for folding each blank into an elongated flat tube, means for delivering the flat tubes in endwise direction, to a pressure conveyor, said pressure conveyor operating at a relatively slower speed than the tubes are fed thereto, whereby the flat tubes are delivered thereto, in lapped relation, means for feeding the tubes, one at a time, from the pressure conveyor, a right angle transfer section adapted to receive said tubes from the pressure conveyor and laterally move them out of the initial path of travel of the tubes, means for accurately positioning the elongated flat tubes on the transfer section, a slitting mechanism positioned to receive said tubes from the transfer section and transversely sever each tube into a plurality of relatively shorter box tubes, and means for delivering the shorter box tubes onto a slow moving conveyor in overlapped relation.
35. In a paper box making machine, means for advancing preformed blanks along a predetermined path in timed relation, glue applying mechanism, means for folding each blank into an elongated flat tube, means for delivering the flat tubes in endwise direction, to a pressure conveyor, said pressure conveyor operating at a relatively slower speed than the tubes are fed thereto, whereby the flat tubes are delivered thereto, in lapped relation, means for feeding the tubes, one at a time, from the pressure conveyor, a right angle transfer section adapted to receive said tubes from the pressure conveyor and laterally move them out of the initial path of travel of the tubes, means for accurately positioning the elongated flat tubes on the transfer section, a slitting mechanism positioned to receive said tubes from the transfer section and transversely sever each tube into a plurality of relatively shorter box tubes, and means for delivering the shorter box tubes onto a slow moving conveyor in overlapped relation.
40. In a paper box making machine, means for advancing preformed blanks along a predetermined path in timed relation, glue applying mechanism, means for folding each blank into an elongated flat tube, means for delivering the flat tubes in endwise direction, to a pressure conveyor, said pressure conveyor operating at a relatively slower speed than the tubes are fed thereto, whereby the flat tubes are delivered thereto, in lapped relation, means for feeding the tubes, one at a time, from the pressure conveyor, a right angle transfer section adapted to receive said tubes from the transfer section and transversely sever each tube into a plurality of relatively shorter box tubes, and means for delivering the shorter box tubes onto a slow moving conveyor in overlapped relation.
45. In a paper box making machine, means for advancing preformed blanks along a predetermined path in timed relation, glue applying mechanism, means for folding each blank into an elongated flat tube, means for delivering the flat tubes in endwise direction, to a pressure conveyor, said pressure conveyor operating at a relatively slower speed than the tubes are fed thereto, whereby the flat tubes are delivered thereto, in lapped relation, means for feeding the tubes, one at a time, from the pressure conveyor, a right angle transfer section adapted to receive said tubes from the transfer section and transversely sever each tube into a plurality of relatively shorter box tubes, and means for delivering the shorter box tubes onto a slow moving conveyor in overlapped relation.

50. In a paper box making machine, means for feeding preformed blanks in timed relation, glue applying mechanism, means for folding each blank into an elongated flat tube, means for delivering the flat tubes in endwise direction, to a pressure conveyor, said pressure conveyor operating at a relatively slower speed than the tubes are fed thereto, whereby the flat tubes are delivered thereto, in lapped relation, means for feeding the tubes, one at a time, from the pressure conveyor, a right angle transfer section adapted to receive said tubes from the transfer section and transversely sever each tube into a plurality of relatively shorter box tubes, and means for delivering the shorter box tubes onto a slow moving conveyor in overlapped relation.
55. In a paper box making machine, means for feeding preformed blanks in timed relation, glue applying mechanism, means for folding each blank into an elongated flat tube, means for delivering the flat tubes in endwise direction, to a pressure conveyor, said pressure conveyor operating at a relatively slower speed than the tubes are fed thereto, whereby the flat tubes are delivered thereto, in lapped relation, means for feeding the tubes, one at a time, from the pressure conveyor, a right angle transfer section adapted to receive said tubes from the transfer section and transversely sever each tube into a plurality of relatively shorter box tubes, and means for delivering the shorter box tubes onto a slow moving conveyor in overlapped relation.
60. In a paper box making machine, means for feeding preformed blanks in timed relation, glue applying mechanism, means for folding each blank into an elongated flat tube, means for delivering the flat tubes in endwise direction, to a pressure conveyor, said pressure conveyor operating at a relatively slower speed than the tubes are fed thereto, whereby the flat tubes are delivered thereto, in lapped relation, means for feeding the tubes, one at a time, from the pressure conveyor, a right angle transfer section adapted to receive said tubes from the transfer section and transversely sever each tube into a plurality of relatively shorter box tubes, and means for delivering the shorter box tubes onto a slow moving conveyor in overlapped relation.
65. In a paper box making machine, means for feeding preformed blanks in timed relation, glue applying mechanism, means for folding each blank into an elongated flat tube, means for delivering the flat tubes in endwise direction, to a pressure conveyor, said pressure conveyor operating at a relatively slower speed than the tubes are fed thereto, whereby the flat tubes are delivered thereto, in lapped relation, means for feeding the tubes, one at a time, from the pressure conveyor, a right angle transfer section adapted to receive said tubes from the transfer section and transversely sever each tube into a plurality of relatively shorter box tubes, and means for delivering the shorter box tubes onto a slow moving conveyor in overlapped relation.
70. In a paper box making machine, means for feeding preformed blanks in timed relation, glue applying mechanism, means for folding each blank into an elongated flat tube, means for delivering the flat tubes in endwise direction, to a pressure conveyor, said pressure conveyor operating at a relatively slower speed than the tubes are fed thereto, whereby the flat tubes are delivered thereto, in lapped relation, means for feeding the tubes, one at a time, from the pressure conveyor, a right angle transfer section adapted to receive said tubes from the transfer section and transversely sever each tube into a plurality of relatively shorter box tubes, and means for delivering the shorter box tubes onto a slow moving conveyor in overlapped relation.
75. In a machine of the class described, means for advancing preformed blanks along a predetermined path in endwise direction, glue applying and folding mechanisms adapted to fold each blank into an elongated open ended tube, means for receiving the freshly glued flat tubes in underlapped relation and applying pressure

thereto to retain the glued wall portions thereof in adhesive relation, until the glue has sufficiently set to prevent the glued seams of the tube from subsequently opening, means for successively feeding the tubes from the pressure applying means in timed relation to the delivery of blanks to the machine, a slitting mechanism disposed out of the initial path of travel of the tubes, means for receiving the elongated tubes from said feeding means and laterally delivering them into the slitting mechanism, whereby each elongated tube is transversely severed into a plurality of relatively shorter box tubes, and means for delivering the relatively shorter box tubes onto a suitable receiving means in overlapped relation.

6. In combination with a machine for making paper box tubes comprising blank feeding, folding, and gluing mechanisms, a pressure unit

5 mounted to receive the glued tubes in lapped relation from the folding and gluing mechanisms and applying pressure to the flat tubes to hold the glued wall portions thereof in adhesive relation, a slitting mechanism laterally offset from the initial travel path of the tubes, means for receiving the tubes from the pressure unit and laterally delivering them to the slitting mechanism, one at a time, in a direction substantially 10 at right angles to the travel path of the tubes through the folding and gluing mechanisms, said slitting mechanism transversely severing each elongated tube into a plurality of relatively shorter box tubes, a receiving conveyer for the relatively shorter box tubes, and means for delivering said shorter box tubes onto the receiving conveyer in overlapped relation.

EDWIN G. STAUDE.
